Specification for Design.

Patented June 6, 1922.

Application filed December 21, 1921. Serial No. 524,024. Term of patent 7 years.

To all whom it may concern:

Be it known that I, HENRY JOSEPH, a citizen of the United States, and residing in the city of Milwaukee, county of Milwaukee, and State of Wisconsin, have invented a new and original and ornamental Design for Rubber Mats, of which the following is a specification, reference being had to the accompanying drawing, forming a part thereof.

The figure is a plan view of the new design of rubber mat, illustrating the arrangement of the fibrous strands in simulation of raffia or other basketry work.

I claim:

The ornamental design for a rubber mat, as shown and described.

In testimony whereof, I have signed my name at Milwaukee, this 17th day of December, 1921.

HENRY JOSEPH.
